CHARLES C. MORGAN, OF NEW YORK, N. Y.

Letters Patent No. 95,253, dated September 28, 1869.

IMPROVED MODE OF FASTENING BUTTONS ON SHOES, &c.

The Schedule referred to in these Letters Patent and making part of the same.

To all whom it may concern:

Be it known that I, CHARLES C. MORGAN, of the city, county, and State of New York, have invented certain new and useful Improvements in the Manner of Fastening Buttons on Shoes and other articles; and I do hereby declare the following to be a full, clear, and exact description of the same, reference being had to the accompanying drawings, making a part of this specification, in which—

Figure 1 represents in perspective the button, strap, and washer, as they would appear when the cloth or leather to which they are to be united is removed.

Figure 2 represents in perspective the preparatory steps taken for an easy putting together of the several parts of the fastening, before they are clinched down in the material.

Figure 3 represents in perspective the position of the several metallic parts, just previous to their being united to each other and the cloth, leather, or other material.

Figure 4 represents a section through washer, strap, cloth, or leather, and eye of the button, as they appear when firmly clinched down and united together.

Similar letters of reference, where they occur in the several figures, denote like parts of the contrivance in all of the drawings.

I am aware that washers have been used in various ways in uniting buttons to cloth or leather. To this, I of course lay no claim, independent of my mode of using and uniting the strap, washer, and button.

As generally, if not universally practised, the strap, neck, shank, or wire, which passes through the washer, is clinched, riveted, or left exposed under the washer, where it is apt to rub or chafe the person. As so terminated, it comes next the skin.

My invention consists in the use of a two-barred or three-holed washer, through which the strap, or its equivalent, which holds the button to the material and the washer, is first inserted with its two ends together. Then said ends spread, each passing separately through lateral openings to that side or surface of the washer where it was first entered, and then clinched down, which gives to the ends of the strap a tucked-under position, and terminates them on top of instead of underneath the washer, which not only makes a strong and unyielding fastening, but one which cannot injure or chafe the skin of the wearer or user.

To enable others skilled in the art to make and use my invention, I will proceed to describe the same with reference to the drawings.

a represents an ordinary shoe-button;

b, the strap;

c, the washer; and

d, the cloth, leather, or other material, to, on, or against which they are fastened.

The washer *c* should have an even number of bars, and an odd number of holes on or in it. I have shown two bars, and consequently three holes, which I have found to be sufficient for any ordinary purpose. More may be, but less cannot well be used.

If the washer *c* be used in a flat condition, which it can be, it makes it tedious to insert the ends of the strap, and to tuck in its ends around the bars and through the openings, and to bring them on top of the washer, or between it and the material to which the button is to be fastened. Still it can be done.

To facilitate the putting together of the button, cloth, or leather, and washer, I bend the latter up into a saddle-form, as shown in figs. 2 and 3. The strap *b*, having been passed through the eye of the button, has its two ends, as shown in fig. 2, curved slightly outward. These ends are together passed through the top or central opening of the three in the washer, and the springing or curved condition of said ends, on being pressed downward, each finds its lateral opening, and passes outward through it, as seen in fig. 3, so that the ends of the strap are upon the same side of the washer that they were entered at, only they were entered together and come out separately. Now, when in this position, and having the cloth or leather interposed between the button and washer, if the washer be flattened out by any applied pressure or force, the several parts will assume the positions shown in fig. 4, and form a neat and strong fastening, and with the ends of the strap terminating above the washer.

The ends of the strap, instead of passing through lateral holes in the washer, may pass to and over the edges or ends of the washer, and be folded down on top thereof. This, though not so good or neat a finish, would still embrace my general plan of terminating the ends of the strap on top of the washer, or between it and the cloth or leather, or tucking them over or on the washer.

Having thus fully described my invention,

What I claim therein as new, and desire to secure by Letters Patent, is—

The combined use of a strap and washer for uniting buttons to cloth, leather, or other material, when the ends of said strap are brought out, over, or on top of said washer, and between it and the cloth, leather, or other material, substantially in the manner and for the purpose described and represented.

CHAS. C. MORGAN.
